THE NORBIS PETERS CO., PHOTO-LITHO., WASHINGTON, D. C.

United States Patent Office.

MATTHEW E. CAMPFIELD, OF NEWARK, NEW JERSEY.

Letters Patent No. 99,155, dated January 25, 1870.

IMPROVEMENT IN MORTISING-MACHINE.

The Schedule referred to in these Letters Patent and making part of the same.

To all whom it may concern:

Be it known that I, MATTHEW E. CAMPFIELD, of the city of Newark, in the county of Essex, and State of New Jersey, have made certain Improvements in Power Mortising-Machines; and declare the following, taken in connection with the accompanying drawings, to be a full and exact description of the same.

The nature of my improvement consists in the manner employed to reverse the chisel, and in adaptation of the parts to that manner.

In the drawings, the same letters refer to the same parts in each figure.

The upright chisel-holding shaft is in two parts. The upper, *a*, is hollow. The lower part, *b*, passing through *a*, is at liberty to turn therein when required.

A collar on the top of *b*, at *c*, under the crank, and one on *b*, just below the end of *a*, holds the two, both moving simultaneously with the crank.

The shaft *b* passes through the ratch-wheel *e*, which has a tubular elongation, that is, a journal, revolving in the bearing *d* on the main frame.

The tube projects below the bearing, and has secured fast to its lower end, under the bearing, the piece *f*, between which and the under side of the bearing is placed the piece *g*, slotted, as shown in Figure 3, to slide against the tube upon *e*, that passes through it.

There is, upon the shaft *b*, a feather or tongue, *i*, sliding in a corresponding groove in the interior of the tube on *e*, to turn the shaft when *e* is turned, and hold it in position when mortising.

The ratch-wheel *e* has a flange on each side, as seen in Figure 2. These flanges are shaped as shown in Figure 5.

A belt, *n*, encircles the wheel between the flanges, having upon it a block, *o*, or blocks, wider than the belt, to catch in the ratches in the flanges on *e*.

A foot-treadle, *p*, fig. 2, has an arm, *q*, jointed thereto. At the top of the arm, is the lever *k*, the fulcrum of the lever being on a level with that part on *f*, upon which *g* rests and slides.

The end of the lever *k* passes through the front *r* of the main frame, entering the notch or recess in the end of *f*, as the foot presses down the treadle *p*. As soon as the foot is lifted and the treadle returns to its

original position, the end of *k* rises above *f*, as shown by dotted lines in fig. 2, and *f* can pass under *k*.

A half revolution is produced by the descent of the weight *s* on one end of the belt *n*, which has been suspended by the block *o*, on the belt *n*, catching in the ratch in the flanges of *e*, and as soon as *k* releases the piece *f*, on the tube on *e*, *f* turns and carries the chisel round to a stop provided at the half turn needed to have the chisel reversed.

The piece *g* lies loose between the sides *t* of *f*, the tube of *e* passing through the slot in *g*. This piece *g* being made longer than would allow it to turn past the end of the lever *k*, at the half turn, one of the projections *u*, fig. 3, catches against the side of *k* and stops it.

The end of *k* is formed cam-fashion, so that in its descent, it pushes *g* from it, so that *g* could turn past it, but as *k* has entered the recess in the end of *f*, it is held from turning until *k* rises above *f*, and then, as *g* has been pushed out at the other end by the cam, at the half turn, it again stops at the side of *k*.

The treadle lifting the weight *s*, the belt *n* having a small counterbalance on the opposite end, on which is the weight *s*, pulls the block *o* into the catch on *e*, and the weight *s* remains suspended until *f* is released, when it of course turns the shaft and chisel.

By this arrangement, the chisel is held steady to its place until the piece is mortised to its proper depth, and the mortised piece descends below and clear of the chisel; then the chisel immediately reverses.

The adjustable table is attached to and moved by the arm *q* on the treadle *p*.

What I claim as my improvements, are—

1. The ratch-wheel *e*, flexible catch *n o*, when constructed and arranged substantially in the manner and for the purposes shown.
2. The cam-lever *k*, arm *q*, and treadle *p*, when used in combination with the ratch-wheel *e*, and flexible catch *n o* in a power mortising-machine, and operated in the manner and for the purposes specified.

M. E. CAMPFIELD.
